Primary Examiner — Susan E Krakower

Assistant Examiner — Jerry Shiuan-Hua Hsu

(57) **CLAIM**

The ornamental design for a vehicle door, as shown and described.

DESCRIPTION

FIG. 1 is a front, top, right perspective view for a first embodiment of a vehicle door, showing the new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof;

FIG. 8 is a front, top, right perspective view for a second embodiment of a vehicle door, showing the new design;

FIG. 9 is a front elevation view thereof;

FIG. 10 is a rear elevation view thereof;

FIG. 11 is a left side view thereof;

FIG. 12 is a right side view thereof;

FIG. 13 is a top plan view thereof; and,

FIG. 14 is a bottom plan view thereof.

The claimed design also includes the mirror image of the vehicle door depicted in FIGS. 1 to 14.

The dash-dot broken lines illustrate a boundary of the claimed design and form no part thereof. The dash-dash broken lines illustrate portions of the vehicle door that form no part of the claimed design.

1 Claim, 14 Drawing Sheets
